UNITED STATES PATENT OFFICE

163,240

RADIATION MEDICAL THERAPY UNIT

Albert J. Bacchieri, Dedham, Mass., assignor to
Tracerlab, Inc., Boston, Mass., a corporation
of Massachusetts

Application December 6, 1950, Serial No. 13,296

Term of patent 14 years

(Cl. D83—1)

To all whom it may concern:

Be it known that I, Albert J. Bacchieri, a citizen of the United States, residing at Dedham, in the county of Norfolk and State of Massachusetts, have invented a new, original, and ornamental Design for Radiation Medical Therapy Unit, of which the following is a specification, reference being had to the accompanying drawings, forming a part hereof, wherein:

Fig. 1 is a view in perspective showing one side and the shutter end of a radiation medical therapy unit showing my novel design,

Fig. 2 is a view of the opposite side and top of the same, and

Fig. 3 is a view on a reduced scale of the lower

end of the unit as shown in Fig. 1, showing the shutter opening and shutter.

I claim:

The ornamental design for a radiation medical therapy unit, as shown.

ALBERT J. BACCHIERI.
